BY
John O'Brien
ATTORNEY.

UNITED STATES PATENT OFFICE.

NATHAN E. VARNEY, OF DENVER, COLORADO.

BOUQUET-HOLDER.

SPECIFICATION forming part of Letters Patent No. 425,967, dated April 15, 1890.

Application filed January 15, 1890. Serial No. 337,020. (No model.)

To all whom it may concern:

Be it known that I, NATHAN E. VARNEY, a citizen of the United States, residing at Denver, in the county of Arapahoe and State of Colorado, have invented certain new and useful Improvements in Bouquet-Holders; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to improvements in bouquet-holders; and the object of my improvement is to provide a device more especially designed for holding what is ordinarily termed a "button-hole bouquet," but the principle of which may also be employed in constructing receptacles for larger bouquets designed for stands or mantels, said device to be simple in construction, economical in cost, reliable, durable, and effective.

20 25 To these ends my invention consists of the features hereinafter described and claimed.

In the drawings is illustrated an embodiment of my invention, in which drawings Figure 1 is a side view of the entire device in elevation. Fig. 2 is an end view of the same. Fig. 3 is a transverse section taken on the line *x x*, Figs. 1 and 2. Fig. 4 is a cross-section taken on the line *y y*, Fig. 5. Fig. 5 shows the removable interior portion of the device 35 open. Fig. 6 is an enlarged view of the same partly closed.

In the views, let the reference-numeral 1 indicate the outer shell, tube, or case, provided with a suitable pin 2, by means of which it 40 may be fastened to the garment upon which the bouquet is to be worn. Tube 1 may be of any desired shape or contour in cross-section and may be formed of any desired size, depending on the number of flowers or the size 45 of the bouquet to be retained therein.

3 is a thin plate of sheet metal, of such dimensions that it may be readily inserted in tube 1. Plate 3 is provided with a small lug or hook 4, adapted to catch on the edge of 50 tube 1 when plate 3 is inserted in the tube.

To plate 3 is secured, by means of small catches 5, or in any other suitable manner, a strip 6, of sponge or other fabric capable of absorbing and retaining moisture. This strip of fabric is about twice the length of plate 3, 55 so that when secured thereon, as shown in Fig. 5, its free portion 7 may be folded over upon the part secured to the plate.

In the use of the device the stems of the flowers forming the bouquet are placed on the 60 fabric 6. The free portion 7 of the moistened fabric is then folded over upon the stems. The moisture-retaining device with its contents, or the inclosed flower-stems, is then inserted in the receptacle of tube 1, which may 65 then be pinned upon the garment where it is to be worn.

If the fabric 6 is suitably moistened before inclosing the stems of the flowers therein, a bouquet thus put up will be kept fresh for a 70 considerable period of time.

It will be observed that the tube 1 may be ornamented to any extent desired, and also that it may be constructed with a suitable base for supporting the flowers upon a mantel 75 or stand without departing from the principle of my invention.

Having thus described my invention, what I claim is—

1. A bouquet-holder consisting of a suitable 80 receptacle, in combination with a moisture-retaining device adapted to enter the receptacle, said device being composed of a plate 3, to which is attached a strip of fabric 6, extending beyond the plate and adapted to fold 85 over thereon, substantially as described.

2. The combination, with a suitable tube, cup, or case, of a plate 3, adapted to enter the same, said plate being provided with a hook 4, adapted to engage the upper edge of the 90 case, and a strip of sponge or other suitable fabric secured to said plate, extending beyond the same and adapted to fold over thereon, substantially as described.

3. The combination, with a tube 1, closed 95 at the bottom and provided with a suitable pin 2, of a moisture-retaining device adapted to enter tube 1, said device consisting of a plate 3, covered with a strip of fabric 6, said strip extending beyond the plate and de- 100

signed to fold over thereon, substantially as described.

4. The combination, with a tube 1, closed at the bottom and provided with a suitable pin 2, of a device adapted to inclose the stems of a bouquet, and consisting of a plate 3, covered with some suitable fabric, which extends beyond the plate and folds over upon the

stems of the flowers preparatory to insertion in the tube, substantially as described.

In testimony whereof I affix my signature in presence of two witnesses.

NATHAN E. VARNEY.
